UNITED STATES PATENT OFFICE.

THOMAS B. TODD, OF SOUTH ST. PAUL, MINNESOTA.

PORTABLE DISPLAY RACK.

Application filed April 4, 1924. Serial No. 704,121.

To all whom it may concern:

Be it known that I, THOMAS B. TODD, a citizen of the United States, residing at South St. Paul, in the county of Dakota and State of Minnesota, have invented certain new and useful Improvements in Portable Display Racks, of which the following is a specification.

My invention relates to display racks in general, and more particularly to a portable rack adapted for use in furniture stores for storing and displaying rugs. The object is to provide a simple, inexpensive and efficient device the use of which enables a merchant 15 to store rugs in any convenient place and move the entire stock of rugs on the device to any part of the store for display purposes.

In the accompanying drawing:

Fig. 1 is a top or plan view of my complete device showing in dotted lines some of the rug racks swung out at various angles.

Fig. 2 is a side elevation of Fig. 1 but showing only two of the oppositely arranged rug racks or hangers.

Fig. 3 is a right hand end elevation of Fig. 2 but showing only one rug rack or hanger.

Fig. 4 is a sectional elevation as on line 4-4 in Fig. 1 including a modification of the main structure.

My device is an elongated, upright, rectangular main frame comprising two horizontally spaced frames made mainly of standard pipe and fittings and mounted on two transversely arranged supports each with two casters, enabling the entire device to be rolled to any suitable location. Rug holding devices are pivotally arranged within said main frame in such a manner that a 40 large number of rugs can be hung in a comparatively small space within the main frame and can be swung out one by one for display.

Referring to the drawing by reference numerals, the upright, rectangular main frame members comprise each an upper horizontal bar 5, a similar lower bar 6 and two vertical end bars or posts 7, all of which are preferably standard pipe. Bars 5 and 45 7 are connected by L's 8, and posts 7 are secured or threaded with their lower ends each in a pipe T 9. Each of said T's has a side outlet 9^a adapted to hold one end of the pipe 6. In the straight bore of two adjacent T's is held a transversely arranged pipe 10 each end of which is bent down-

wardly and its extremity adapted to rotatably hold the stem of a caster 11.

The rug hanging parts of my device comprise a plurality of triangular frames pivotally mounted within the frame described as follows:

At each end of the main frame I provide two vertically spaced horizontal plates of isosceles triangle form the upper plate 65 designated 12 and the lower plate 13. If cast these plates are provided with integral collars 13^a bored for posts 7 and the inner corner of the plate has a central collar 13^b bored for a vertical brace post 14. All four 70 plates are arranged with their equal sides tapering inwardly and the brace post is located at the convergence of said equal sides; and adjacent to said equal sides I provide a row of holes 15. Said holes 15 75 in the upper plate 12 register vertically with the holes 15 in the lower plate 13. In each such pair of holes is rotatably held the vertical arm 16^a of the previously mentioned rug 80 rack 16. As mentioned each such rack is triangular and comprises the vertical arm 16^a, from the upper end of which extends a horizontal integral arm 16^b braced from the lower part of arm 16^a by an angle brace 16^c. The lower end of brace 16^c may be secured 85 in the angle of a so-called Y pipe fitting 17 which also supports the lower end of arm 16^a and acts as a supporting bearing on plate 13. The bores 15 in the opposite pairs 90 of plates 12 and 13 are arranged in staggered relation so that the rug racks 16 may overlap almost their entire length. The rugs are of course hung one on each rack arm 16^b about as indicated in dotted lines 95 17 in Fig. 2.

In Fig. 4 I have shown how the inner ends of plates 12-13 and the pipe post 14 may be mounted absolutely rigid, namely by providing a cross bar (pipe) 18 connecting pipes 6 horizontally, a pipe T 19 on said pipe 18 adapted to receive and hold the lower end of pipe 14 which is passed through the inner bore of plate 13. In this case the upper end of pipe 14 may be threaded or otherwise secured to plate 12 as at 13^b. Thus the plates 12 and 13 are absolutely rigid, a desirable construction for large display racks where a large number of rugs would be very heavy.

In Fig. 3 I have shown only one rug rack 110 16 swung out from the frame. Its upright arm 16^b is inclined outwardly at its upper

end, that is the bores 15 in the upper plate are slightly further out than the bores 15 in the lower plate 13 causing the frame swinging therein to swing outwardly of its own weight and the added weight of a rug on each such rack.

It is obvious that a large number of rugs can be stored in my device in the minimum space and the main feature is that the entire supply of rugs thus stored can be moved to any place in a store where a salesman can swing the racks out alternately at either side of the device and display the rugs. The racks swung out from both sides will counterbalance each other but stability of the entire device is insured by merely making the transverse supports 10 amply long.

The operation of the device having already been fully disclosed I will merely further state that considerable variation in construction may be required to suit various conditions, for example, two sets of rug racks may be arranged to be swung out from one side only or the racks may be arranged far enough apart so as not to be overlapped, but such variations fall within the scope of the invention. Another feature is that a large number of rugs can readily be moved with small effort to any part of a store in various kinds of light to properly display the rugs to prospective buyers.

What I claim is:

In a portable display rack a pair of horizontally disposed, spaced supports mounted on casters, a main frame comprising two vertically disposed quadrangular frames mounted on said supports in spaced relation, a plurality of display racks mounted between said vertical frames and adapted to be swung horizontally and outwardly from the frame, said display racks comprising each a vertically disposed triangular frame with an upright arm, an integral arm extending horizontally from the upper end of the vertical arm and an angular brace connecting said upright and horizontal arms, said racks being swingable each in two vertically spaced horizontal plates secured to the adjacent upright members at each end of the main frame, said plates having rows of vertically registering apertures, each upright arm being pivotally held near its upper end in an aperture in the upper plate and its lower end in a registering aperture in the lower plate, and means for vertically supporting the inner end of each set of plates comprising a vertically arranged post connecting said plates, a cross bar arranged transversely in the lower part of the main frame and operatively connected with the lower end of said post.

In testimony whereof I affix my signature.

THOMAS B. TODD.
